Wm. J. Neat
ATTORNEY

UNITED STATES PATENT OFFICE.

GEORGE GUSOFF, OF NEW YORK, N. Y.

COMBINATION VANITY BOX.

Application filed June 23, 1923. Serial No. 647,234.

To all whom it may concern:

Be it known that I, GEORGE GUSOFF, a citizen of the United States, residing at New York, in the county of Bronx and State of New York, have invented certain new and useful Improvements in Combination Vanity Boxes, of which the following is a specification.

This invention relates generally to the construction of vanity cases.

The invention consists of a receptacle for powder and rouge and an applicator therefor, and includes a mirror element distinct from the receptacle proper and the cover member. The mirror is mounted to automatically rise to a convenient position for use when the receptacle is opened, leaving the cover and body portions of the receptacle each available for use as material-containing compartments.

Other features of the invention include a removable supporting framework to fit the inside of the main body portion of the receptacle and to provide a holder for a "compact" or cake of powder or other cosmetic. The holder thus provided is adapted also to receive a powder puff or other applicator for the powder. The mirror element referred to is adapted to be closed down against the powder puff and the cover of the receptacle containing a supply of rouge or other material and a puff or applicator is in turn adapted to be closed down against the mirror thereby providing a compact assemblage of the various parts when not in use.

In the drawings, in which a preferred embodiment of the invention has been selected for illustration,

Figure 1 is a view in perspective of a vanity case embodying the invention and showing the structure in its opened condition.

Figure 2 is a view in vertical section of the parts shown in Figure 1.

Figure 3 is a view similar to Figure 2 showing the parts in closed condition.

Figure 4 is a view from underneath of a container device adapted to be fitted to the receptacle cover member as in Figure 1.

Figure 5 is a view of a combined mirror and holder element adapted to be fitted to the main body portion of the receptacle as shown in Figure 1.

Referring to the drawings for a more detailed description of the invention, a relatively flat container 10 is provided with a hinged cover member 11 having a depth sufficient to itself serve as a container. The main body portion 10 of the container is arranged to receive a supporting base member 12 for a mirror element 13 having a spring hinge connection at 14 with its support and arranged to automatically assume a vertically inclined position, as indicated in Figure 2, when the cover member 11 is swung back to opened position.

The mirror supporting member 12 includes a pair of diverging base members 15 arranged to rest on the inner surface of the base of the container and provided at their free ends with upstanding bowed terminal members 16 adapted to fit beneath an annular shoulder 17 formed on the container to serve as a stop for the cover member. This disposition of the members 16 securely anchors the forked members 15 and the mirror support in position, so that the upward swing of the mirror to its elevated position will not cause the mirror support to be thrown or lifted out of its position.

It will be seen that the mirror supporting member includes a shelf-like element 18 having the form of a segment of a circle and to the upper surface of which the mirror element is hinged. It will be seen that the member 18 forms a firm and rigid support for the mirror and also serves as a stop as at the point 19 against which the mirror frame engages in its raised position, and also helps to hold the compact in place.

The container is adapted to receive a cake or compact of powder 20 held in place by the bowed members 16 and a powder puff 21 which is arranged to rest on the compact as indicated in Figures 2 and 3 of the drawing and against which the mirror 13 rests in its lowered or closed position. The mirror with its supporting framework may be removed bodily from the container by springing the frame member inwardly from its engagement at 22 beneath the shoulder 17 at the right hand side of the container as shown in Figure 2.

The cover member 11 is provided with an annular member 23 having a flange 24 at its

inner periphery which serves as a spacing member to hold the annular member spaced from the inside surface of the cover and thereby form a rounded opening 25 to serve as a compartment for a cake or compact 26 of rouge or the like. A correspondingly shaped puff 27 also fits into the opening 25 on top of the cake 26.

In order to hold the puff 27 and the compact 26 in position in the compartment 25 in the cover a U-shaped member 27' is mounted beneath the annular member 23 and provided with outwardly bent hook members 28 which extend through openings 29 formed in the annular member 23 adjacent the opening 25. It will be seen that the hook members 28 overhang the opposite edges of the opening 24 so as to engage and hold the cake or rouge 26 and the powder puff 27 in position in the cover compartment.

It will be seen that with the construction described a device of the general type described is provided which makes use of compartment space for materials in both the receptacle and its cover member, and which includes a mirror construction in which a mirror element automatically rises to a fixed angular position convenient for use upon the lifting of the cover member.

It will be understood that for the purposes of this specification, and in the claims, the terms "receptacle" and "cover" may be interchangeable, for instance, in the sense that the combined mirror-supporting and compact-holding member might be positioned in either the receptacle or the cover.

What I claim is:—

1. In a vanity case construction, a receptacle forming a compartment for cosmetic material, a hinged cover member forming another compartment for material, a mirror-supporting and compact-holding element removably positioned in the receptacle, a mirror having a hinged mounting on the element, and means for automatically raising the mirror to a convenient position for use when the cover member is lifted.

2. In a vanity case construction, a receptacle forming a compartment for cosmetic material, a cover member hinged to the receptacle, a mirror element, a support for the mirror element including an anchoring member extending along the inner surface of the bottom of the receptacle and having an upwardly extending lug, a shoulder on the receptacle beneath which the lug engages, and a spring hinge connection between the mirror and its support.

3. In a vanity case construction, a receptacle forming a compartment for cosmetic material, a cover member hinged to the receptacle, a mirror element, a support for the mirror fitting one side of the inner contour of the receptacle and including a mirror sup-

porting member lying substantially flush with the upper edge of the receptacle, and a spring hinge connection between the mirror element and an inner portion of the upper surface of the support, whereby the mirror is normally impelled to take a position inclined slightly to the perpendicular and engaging the surface of the support as a stop.

4. In a vanity case construction, a receptacle forming a compartment for cosmetic material, a cover member hinged to the receptacle, a mirror element, a support for the mirror removably fitting an inner side of the receptacle and including a mirror supporting member lying substantially flush with the upper edge of the receptacle, and a spring hinge connection between the upper surface of the support and the mirror, whereby the mirror is normally impelled to take a position inclined slightly to the vertical and engaging the upper surface of the support as a stop, diverging anchoring members extending across the inner surface of the bottom of the receptacle, upwardly extending lugs on the free ends of the anchoring members, and a shoulder on the receptacle beneath which the lugs engage.

5. In a vanity case construction, a receptacle forming a compartment, a cover member hinged to the receptacle, a mirror element, a support for the mirror element removably fitting an inner side of the receptacle and including a mirror supporting member lying substantially flush with the upper edge of the receptacle, and a spring hinge connection between the upper surface of the support and the mirror whereby the mirror is normally impelled to take a vertical position resting against the support as a stop, an annular shoulder on the receptacle interengaged by the mirror support, diverging anchoring members extending from the support across the inner surface of the bottom of the receptacle, upwardly extending lugs on the free ends of the anchoring members engaging beneath the shoulder, a powder compact and a powder puff fitting in the receptacle, a compartment in the cover member for a rouge compact and a puff, and spring hook members overlying the edges of the compartment to hold the contents in place.

6. In a vanity case construction, a receptacle, a detachable container therein provided with means for retaining it in the receptacle, said container having a shelf at one side thereof, a mirror hinged to the shelf and a cover for the vanity case.

7. In a vanity case construction, a receptacle, a detachable container therein provided with means for retaining it in the receptacle, a mirror hinged to the container, a cover for the receptacle having a compartment for a rouge compact and a puff and spring hook members overlying the edges of

the compartment to hold the contents in place.

8. In a vanity case construction, a receptacle, a combined compact-holder and mirror support within the receptacle, said compact-holder having portions fitting the bottom of the receptacle and other portions fitting opposed inner side wall surfaces, a shelf on one

of said opposed inner side wall fitting portions and a mirror hinged to said shelf.

10

In testimony whereof I affix my signature in presence of a witness.

GEORGE GUSSOFF.

Witness:

ARTHUR PALUMBO.
